UNITED STATES PATENT OFFICE.

WILLIS K. HODGMAN, JR., OF TAUNTON, MASSACHUSETTS.

MECHANICAL MOVEMENT AND PRINTING-PRESS INVOLVING THE SAME.

1,302,366.

Specification of Letters Patent. Patented Apr. 29, 1919.

Application filed September 8, 1917. Serial No. 190,317.

To all whom it may concern:

Be it known that I, WILLIS K. HODGMAN, Jr., a citizen of the United States, and a resident of Taunton, in the county of Bristol and State of Massachusetts, have invented an Improvement in Mechanical Movements and Printing-Presses Involving the Same, of which the following description, in connection with the accompanying drawings, is a specification, like characters on the drawings representing like parts.

This invention relates to a mechanical movement capable of use in many and varying relations and also to printing presses as illustrative of one application of such mechanical movement and wherein such movement has peculiar advantages.

In order that the principle of the invention may be readily understood, I have disclosed a single type or embodiment thereof in the accompanying drawings, wherein—

Figure 1 is a view in longitudinal section of a printing press embodying my invention and having applied to and incorporated therein the mechanical movement also constituting a portion of my invention, both ends of the press being broken away;

Fig. 2 is a plan view of the construction shown in Fig. 1;

Fig. 3 is a view partly in end elevation and partly in transverse section of the construction shown in Fig. 1;

Fig. 4 is a detail showing certain of the parts represented in Fig. 1, but differently positioned;

Fig. 5 is a transverse section upon the line 5—5 of Fig. 4; and

Fig. 6 is a longitudinal section upon the line 6—6 of Fig. 4.

My invention in part comprehends a mechanical movement *per se* and which is capable of use in many different relations, and it also comprehends a printing press embodying and having incorporated therein such mechanical movement, inasmuch as such movement peculiarly functions with a printing press in effecting the movements thereof. I shall therefore proceed to describe a printing press having embodied therein such mechanical movement without, however, limiting the scope of the invention to a printing press. The printing press herein represented is of the so-called two revolution bed and cylinder type. It is, however, distinctly to be understood that my invention may be ap-

plied not only to other mechanisms and apparatus than printing presses but also that it may be applied to other types of printing presses than that represented.

Referring briefly to the mechanical movement herein disclosed, without limiting the same thereto, I desire to point out that it is peculiarly adapted for converting rotary motion into rectilinearly reciprocating motion in a reciprocable member and for producing rotary motion, preferably but not necessarily intermittent, in one direction in a rotatable member, so that the surface speed of the said rotatable member shall conform at all times in degree to that of the said reciprocable member. Referring merely to that application of my invention herein disclosed, the reciprocable member is typified as the bed of a printing press and the rotatable member as the impression cylinder thereof.

In carrying out my invention I provide a driving member which is preferably a continuously running shaft and loosely mount thereon or concentrically therewith a rotatable member herein typified as a crank or crank arm, but which may be of any other suitable type or form, as for example a disk, which is referred to merely as one of a number of types of rotating members that may be employed.

Before proceeding to describe in detail the disclosed application of my invention, I will point out certain characteristic movements of a two revolution bed and cylinder printing press in order that the peculiar applicability thereto of the disclosed mechanical movement may be appreciated.

In the usual operation of a printing press of the disclosed type, the bed is propelled first in one and then in the opposite direction at a uniform speed, the direction of motion of the bed being reversed at the end of the uniform speed portion of its travel by gradually slowing down the movement of the bed in the one direction until it is brought to rest and by then gradually accelerating its movement in the opposite direction until it is brought up to the said uniform speed which is maintained until a gradual slowing down is effected toward the end of its movement in the other direction. The cylinder of the press in the meantime rotates in one direction and in the disclosed embodiment of my invention such rotation is

periodically stopped as will be hereinafter more fully set forth. The speed of rotation of the cylinder in a two revolution bed and cylinder printing press is normally that of 5 the said uniform speed of the bed. During the printing stroke of the bed, the surfaces of the bed and cylinder are then traveling for a time at the same speed and therefore paper carried on the surface of the cylinder 10 may be pressed with a rolling action against a printing surface carried by the bed. During the return movement of the bed and also during the printing stroke in the periods of accelerated and retarded speed immediately 15 preceding and following the described uniform speed portion of the stroke of the bed, the surface of the cylinder and printing surface carried by the bed must be separated in two revolution bed and cylinder printing 20 presses of previously existing types.

By incorporating in a printing press of the two revolution bed and cylinder type, the mechanical movement of my invention, I obtain certain advantages which will be 25 referred to or made fully evident hereinafter but certain of which I will now briefly set forth.

By adapting and applying the said mechanical movement to a printing press of 30 the two revolution bed and cylinder type, the printing can be done during any part of the printing stroke of the bed clear to the actual stop of the bed at the end of its printing stroke, and is not limited to the 35 uniform speed portion of the stroke of the bed. More of the complete cycle may be utilized to reverse the direction of motion of the bed, thus reducing the strain on the parts. The total stroke of the bed may be 40 cut down in length due to the fact that printing may take place up to the arrival of the bed on dead center. The cylinder of the press may be reduced in diameter due to the shorter stroke of the bed, and due also to the 45 fact that the surface speed of the cylinder varies at all times with that of the bed. The gripper action may be made to operate and preferably is made to operate while the cylinder is running at less than said uniform 50 speed. For the foregoing reasons, the printing press is capable of considerably increased speed over the usual type of two revolution bed and cylinder press.

I have herein disclosed a sheet delivery 55 and its relation to the said mechanical movement of my invention which is such that the sheet is stopped so that it may be piled while stopped, inasmuch as the sheet delivery stops with the press on dead center, and therefore 60 at exactly the right time to effect such described sheet piling.

I am enabled in the practice of my invention to eliminate considerable weight of material since my press is shorter and lower 65 than the usual two revolution press and also

because the easier reversal in movement thereof does not necessitate so much dead weight in the frame to absorb the inertia of the bed movement. I am also enabled to do away with many parts heretofore employed in effecting the bed motion such for example as cams, springs, swinging shoes, universal joints and sliding gears.

By reason of the employment of the said mechanical movement in a printing press of 75 the two revolution type, all the time between the beginning of a printing stroke and the beginning of actual printing is available to register the cylinder with the bed instead of the very short time allowed on the usual two 80 revolution press. Furthermore since the driving shaft runs at a speed permitting it to be belted to direct, no auxiliary driving shaft is required, and I am thus enabled to eliminate mechanism and to reduce the 85 amount of floor space heretofore required with two revolution bed and cylinder presses.

These and other advantages accrue from the employment of the said mechanical movement in a two revolution bed and cylinder printing press, but as previously stated, my invention is in no wise limited to such use or adaptation of the said mechanical movement.

Without in any wise limiting my invention thereto, I will now proceed to describe in detail a two revolution bed and cylinder printing press having the said mechanical movement of my invention applied thereto, and will set forth certain slight variations 100 in type of such character of press without, however, attempting to disclose all forms or types of such general character of press to which the said mechanical movement may be applied.

Referring more particularly to the drawings, the drive shaft is indicated in the various views at 1, it being driven in any suitable manner from any suitable source of power as for example by the employment of 110 a combination fly wheel pulley 2 mounted thereon. The said shaft is mounted in suitable bearings not necessary particularly to refer to.

Fast upon the inner end of the said drive 115 shaft 1 is a gear 3 shown most clearly in Fig. 5 and which I term the bed driving shaft gear. Loosely mounted upon the said shaft 1 and preferably adjacent to said gear 3 is a crank or crank arm 4 which may partake of any suitable form or shape and which carries a crank pin 5 fast thereon. Rotatable upon the said crank pin 5 is a bed driving gear 6 preferably of the width indicated in Figs. 5 and 6, so that it may mesh both with 120 the bed driving shaft gear 3 and with the endless bed rack, a portion of which is indicated at 7.

The reciprocable bed of the press is indicated at 8 and to the latter are secured the 130

outer reversing shoes 9, 10 and the rack hanger 11 which carries the inner reversing shoes 12, 13, as well as the said endless bed rack 7.

5 Rotatable upon the crank pin 5 is a so-called reversing roller 14, which at either end of the movement of the bed enters between the inner and outer reversing shoes thereat.

10 Preferably I provide suitable means cooperating with said crank arm 4 and related parts to maintain the same in position during the uniform speed portion of the travel of the bed. For this purpose I have herein 15 represented a locking strip 15 secured to the rack hanger 11 and extending longitudinally of the bed. With said locking strip are adapted to engage at the proper time locking members or rollers 16, 16, 17, 17, 20 which are fast in pairs to the crank arm 4, as clearly indicated in Fig. 4.

The bed 8 of the press is supported in any suitable manner as for example on sets of bed rollers 18, 18 mounted on tracks or ways 25 19, 19, 19, forming a part of the frame work of the printing press.

The bed 8 has fast thereto a longitudinally extending rack 20 constituting a cylinder driving rack and which meshes with a 30 cylinder driving shaft gear 21 shown most clearly in Fig. 2. The said gear 21 is loose upon a cylinder driving shaft 22 mounted in bearings 23, 23', 23''. Said cylinder driving rack 20 also meshes with an auxiliary cylinder driving shaft gear 24, which is fast on an auxiliary cylinder driving shaft 25 mounted in bearings 26, 26 in parallelism with the cylinder driving shaft 22. The said auxiliary cylinder driving shaft 25 has 35 also fast thereon an auxiliary cylinder driving shaft gear 27 which meshes with a cylinder driving shaft gear 28 loosely mounted on the cylinder driving shaft 22. Either of the cylinder driving shaft gears 21 or 28, which 40 45 it will be observed are rotated in opposite directions, may be made temporarily fast to the cylinder driving shaft 22 in any suitable manner and preferably by a toothed clutch indicated generally at 29 in Fig. 2. The said clutch is slidably mounted upon the cylinder driving shaft 22 but is not rotatable relatively thereto. Any suitable means may be provided to slide said clutch upon the shaft 22. For the purpose I have 50 55 herein represented in Fig. 3 a clutch yoke 30 carried by a clutch lever 31 pivoted centrally at 32 upon the framing of the machine and having pivotally connected to its outer end at 33 a link 34 pivotally connected at 35 to a lever 36 pivoted at 37 upon the framing of the machine and having at its inner end a roller 38 engaging the groove in a cam 39 fast upon the sleeve of crank arm 4.

60 The cylinder driving shaft 22 has fast 65 upon its outer end a cylinder driving gear

40 shown in Figs. 2 and 3, and which meshes with a cylinder gear 41 fast to the shaft 42 of the impression cylinder 43.

During the engagement of the bed driving gear 6 with either of the straight sections of the endless bed rack 7, the bed 8 of the press is driven at a uniform speed in one direction or the other and the locking strip 15 engaging with the locking rollers 16, 17 holds the crank 4 so that a vertical line 70 through the center of the crank pin 5 thereof also passes through the center of the driving shaft 1, as is clearly evident from Fig. 4. At the same time one or the other of the cylinder driving shaft gears 21, 28 is fast to the 80 cylinder driving shaft 22 so that the impression cylinder 43 is rotated in the desired direction and at the same surface speed as that of the bed 8. When the bed 8 has moved along until one or the other of the 85 curved ends of the endless bed rack 7 has been reached, the locking strip 15 passes from between the locking rollers 16, 17, so that the crank 4 is free to rotate upon the driving shaft 1, and does rotate in the same 90 direction of rotation as the said driving shaft 1, the said bed driving gear 6 meshing with the teeth in the curved end of the endless bed rack 7, and the reversing roller 14 being engaged between one or the other of 95 the outer reversing shoes 9, 10 and its corresponding inner reversing shoe 12, 13. For the first part of the rotating movement of the crank 4, the motion of the bed is continued in the same direction in which it had 100 been going, but the speed thereof is gradually diminished until the bed is stopped at the time the reverse curved part 44 of the endless bed rack, the reverse curved part of the inner shoe and the corresponding reverse curved part 45 of the outer reversing shoe, represented in this form of my invention, have been reached. While my invention is in no wise limited thereto, I preferably provide said reverse curved portions 105 110 115 44, 45 and the corresponding reverse curved portion of the inner shoe, so as to prolong the period at which the bed dwells at rest, and in this form of my invention advantage is taken of such relatively prolonged or appreciable dwell in order to shift the toothed clutch 29 by the mechanism hereinbefore described so that it clutches the other of the cylinder driving gears and makes it temporarily fast to the cylinder driving shaft 22. 120

As the crank 4 continues its rotation and the bed driving gear 6 and the reversing roller 14 pass beyond the reverse curved portions 44, 45 of the endless bed rack and reversing shoes, the bed 8 is gradually 125 brought up to speed in the opposite direction to that in which it has been traveling and the hereinbefore referred to uniform speed is again secured when the bed driving gear 6 engages the other straight portion of 130

the endless bed rack 7. The crank 4 having made one half a rotation while in engagement with one of the curved portions of the rack, it is again locked in position by the 5 locking strip 15 engaging with the locking rollers 16, 17 and the said uniform speed is maintained until the bed approaches the end of its movement in the opposite direction.

Inasmuch as the impression cylinder 43 is 10 driven from the cylinder driving rack 20 secured to the bed 8, the speed of said cylinder 43 is thereby caused to conform in degree or rate to that of the said bed 8, but the direction of rotation of the said cylinder 43 15 is the same as before due to the other one of the cylinder driving shaft gears having been made fast to the cylinder driving shaft by the toothed clutch 29.

With each of the forms of my invention I 20 may provide some suitable sheet delivery although my invention is in no wise limited to such provision. Since, however, the mechanical movement herein disclosed lends itself particularly to a sheet delivery, I 25 have provided the same and have represented it in connection with that form of my invention shown in the drawings. I will proceed to describe in detail that selected form of sheet delivery herein shown without 30 limiting myself thereto.

Referring to Figs. 1 and 3 of the drawing, I have indicated the so-called down tapes at 87. The said tapes carry the sheet in the usual manner to the usual reciprocating delivery carriage which carries the sheet out to piling position on its forward stroke and has the top run of its tapes 89 held in any suitable manner, not herein indicated, on the return stroke, so that the sheet is 40 driven off onto the pile in a manner not herein necessary more fully to describe. The sheets are preferably delivered to a table mounted for downward movement at the right of Fig. 1 but the same has been 45 omitted from the drawing for lack of space.

Due to the gradual manner in which the bed 8 is started and stopped at the ends of its stroke, the delivery carriage, which has approximately the same length of stroke as 50 the bed, may be driven from the bed, and thus an exceedingly advantageous sheet delivery is secured.

For this purpose any suitable operative connections may be provided, but herein I 55 have represented a sprocket gear 90 fast upon the auxiliary cylinder driving gear 25 and with which engages a sprocket chain 91 horizontally arranged and passing about and driving a similar sprocket gear 92 upon 60 a stud 93 and having fast therewith a gear 94 which in turn meshes with a gear 95 fast on a delivery shaft 96. Upon each end of the said delivery shaft 96 are sprocket gears 97 about which pass sprocket chains 98 that 65 pass about and drive similar sprocket gears

99 mounted upon studs 100 and having fast with them the delivery carriage pinions 101 which mesh with the delivery carriage racks 102, fastened to each side of the delivery carriage 88 thereby causing said carriage to 70 be reciprocated upon the carriage tracks.

As the delivery carriage approaches its extreme forward position over the pile of sheets, the bed is approaching the end of its stroke and as the bed gradually slows down 75 and stops and dwells momentarily before starting back, the delivery carriage 88, inasmuch as it is driven from the bed 8, comes to a full stop gradually and dwells in a like manner. Therefore the sheet is brought 80 gradually to a stop and remains at a standstill for an instant before the carriage starts to roll from beneath it, thus making it easy to deliver any size sheet accurately to the pile without adding additional parts to stop 85 the sheet or to force it down on the pile. Inasmuch as the front of the carriage clears the tail of the sheet by a considerable distance on the back stroke of the carriage, the sheet is given plenty of time to settle onto the pile 90 of sheets and therefore there is no danger that the carriage will strike such topmost sheet upon the next forward stroke of the delivery carriage.

With this long stroke carriage driven directly from the bed of the printing press, a pile of sheets extending to the floor may be formed by equipping the delivery table (not herein shown) with any well known lowering device, also not shown.

The carriage due to being driven from a solid steady driver (the bed) may be given a long stroke, *i. e.* approximately the stroke of the bed. Due to said long stroke the front end of the carriage clears the tail end 100 of the sheet by a considerable distance on the back stroke of the carriage and hence the sheet has plenty of time to settle.

In the preferred form of my invention, namely, that shown in the drawings, the action of the loosely mounted rotatable member therein typified as a crank is intermittent, and due to its action with the reverse curve portion of the endless rack and reversing shoes, time is obtained to operate 110 part of the mechanism controlling the action of the printing cylinder, so that the surface speed of the cylinder may be exactly synchronized to that of the bed, and thus they both stop and start together at the 120 times that the bed is at the extreme ends of its stroke, and during the printing stroke the surface speeds of the cylinder and bed are exactly the same and in the same direction for the whole of the printing stroke 125 from dead center to dead center. On the return stroke, while the surface speeds of the said two parts are the same, they are traveling in opposite directions, and therefore their surfaces must be slightly sep- 130

arated. Such separation is effected in the usual manner not herein necessary more fully to disclose. The press is therefore what may be defined as a two revolution 5 stop cylinder printing press.

Having thus described one illustrative embodiment of my invention, I desire it to be understood that although specific terms are employed, they are used in a generic and 10 descriptive sense and not for purposes of limitation, the scope of the invention being set forth in the following claims:

1. A mechanical movement comprising a reciprocable member, a driving shaft, a driving member fast on said shaft, a rotatory member concentric with said shaft, a driving member mounted on said rotatory member eccentrically with respect to said shaft, and having driving relation with said reciprocable member and with the driving member fast on said driving shaft, said parts being constructed, coöperating and operatively connected to drive the reciprocable member at a uniform speed during a part 20 of its forward and backward strokes, and to cause it to remain appreciably at rest at the end of each of said strokes.

2. A mechanical movement comprising a reciprocable member, a driving shaft, a driving member fast on said shaft, a rotatory member concentric with but loose with respect to said shaft, a driving member eccentrically mounted on said rotatory member with respect to said driving shaft, and having driving relation with said reciprocable member and with the driving member on said driving shaft, said parts being constructed, coöperating and operatively connected to drive the reciprocable member at a uniform speed during a part 30 of its forward and backward strokes, and to cause it to remain appreciably at rest at the end of each of said strokes.

3. A mechanical movement comprising a reciprocable member, a driving shaft, a driving member fast on said shaft, an intermittently rotatory member concentric with said shaft, a member mounted on said rotatory member eccentrically with respect to said driving shaft and having driving relation with said reciprocable member and with the driving member on said driving shaft, said parts being constructed, coöperating and operatively connected to drive the reciprocable 40 member at a uniform speed during a part of its forward and backward strokes, and to cause it to remain appreciably at rest at the end of each of said strokes.

4. A mechanical movement comprising in 45 combination, a reciprocable member, a driving shaft having a driving gear fast thereon, an intermittently rotatory member loosely mounted upon said shaft and a gear carried thereby eccentric with respect to said driving shaft, and having meshing relation

with said driving gear and with the reciprocable member, said reciprocable member having formations coöperating with said driving gear and with said intermittently rotatory member whereby said reciprocable 70 member is driven at a uniform speed during a part of its forward and backward strokes, and whereby it is caused to remain appreciably at rest at the end of each of said strokes.

5. A mechanical movement comprising in 75 combination a reciprocable member, an endless rack secured thereto, a driving shaft, a driving gear fast on said shaft, a rotatory member concentric with but loose from said shaft, a gear eccentrically mounted on said 80 rotatory member and meshing with said driving gear and with said endless rack, said parts being constructed, coöperating and operatively connected to drive the reciprocable member at a uniform speed during a part 85 of its forward and backward strokes, and to cause it to remain appreciably at rest at the end of each of said strokes.

6. A mechanical movement comprising in 90 combination a reciprocable member, an endless rack secured thereto, a driving shaft, a driving gear fast on said shaft, an intermittently rotatory member concentric with said shaft, a gear eccentrically mounted on said 95 rotatory member, an meshing with said driving gear and said endless rack, said parts being constructed, coöperating and operatively connected to drive the reciprocable member at a uniform speed during a part of its forward and backward strokes, and to cause it to remain appreciably at rest at the end of each of said strokes.

7. A mechanical movement comprising a reciprocable member, a driving shaft, a driving member fast on said shaft, a rotatory 105 member concentric with said shaft, a driving member eccentrically mounted on said rotatory member and having driving relation with said reciprocable member and with the driving member fast on said driving shaft, means periodically to lock said rotatory member with respect to the driving shaft, said parts being constructed, coöperating and operatively connected to drive the reciprocable member at a uniform speed 110 during a part of its forward and backward strokes, and to cause it to remain appreciably at rest at the end of each of said strokes.

8. A mechanical movement comprising a 115 reciprocable member, a driving shaft, a driving member fast on said shaft, a rotatory member concentric with said shaft, a driving member eccentrically mounted on said rotatory member and having driving relation with said reciprocable member and with the driving member fast on said driving shaft, locking means extending along the path of the reciprocable member periodically to lock said rotatory member with re- 120 125 130

spect to the driving shaft, said parts being constructed, coöperating and operatively connected to drive the reciprocable member at a uniform speed during a part of its forward and backward strokes, and to cause it to remain appreciably at rest at the end of each of said strokes.

9. A mechanical movement comprising a reciprocable member, a driving shaft, a driving member fast on said shaft, a rotatory member concentric with said shaft, a driving member eccentrically mounted on said rotatory member and having driving relation with said reciprocable member and with the driving member fast on said driving shaft, a strip extending longitudinally of said reciprocable member and adapted periodically to lock said rotatory member by engagement therewith, said parts being constructed, co-operating and operatively connected to drive the reciprocable member at a uniform speed during a part of its forward and backward strokes, and to cause it to remain appreciably at rest at the end of each of said strokes.

10. A mechanical movement comprising a reciprocable member, a driving shaft, a driving member fast on said shaft, a rotatory member concentric with said shaft, a driving member eccentrically mounted on said rotatory member and having driving relation with said reciprocable member and with the driving member fast on said driving shaft, means whereby said rotatory member is locked from rotation during travel of said reciprocable member in each direction, and is permitted to make one half rotation when unlocked, said reciprocable member having reversely curved end portions coöperating with the said driving member, whereby to effect the driving of said reciprocable member at a uniform speed during a part of its forward and backward strokes and whereby to cause said reciprocable member to remain appreciably at rest at the end of each of said strokes.

11. A mechanical movement comprising in combination, a reciprocable member, a rack carried thereby, a driving shaft, a driving gear fast on said shaft, a rotatory member concentric with but loose with respect to said shaft, a gear eccentrically mounted on said rotatory member and meshing with said driving gear and said rack, means periodically to lock said rotatory member with respect to said driving shaft, said parts being constructed, coöperating and operatively connected to drive the reciprocable member at a uniform speed during a part of its forward and backward strokes, and to cause it to remain appreciably at rest at the end of each of said strokes.

12. A mechanical movement comprising a rack, a driving shaft, a driving gear fast

thereon, a crank loose upon said shaft, a gear eccentrically carried by said crank, and meshing with said rack and said driving gear, means whereby said crank is locked with respect to the driving shaft during the uniform speed travel of said rack in opposite directions but is unlocked therefrom while said rack is being brought to a position of rest and is starting therefrom, said parts being constructed, coöperating and operatively connected to drive the reciprocable member at a uniform speed during a part of its forward and backward strokes, and to cause it to remain appreciably at rest at the end of each of said strokes.

13. A printing press comprising in combination, a reciprocable bed, means to drive said bed in each direction including means to start the bed from a position of rest, to bring it gradually to desired uniform speed, to maintain said uniform speed throughout the major portion of the movement of the bed in both directions of reciprocation, and gradually to bring it to a position of rest, a cylinder rotatable in one direction only, and means for causing the surface speed of the cylinder to conform in degree with that of the bed at all times during the described stroke of the bed.

14. A printing press comprising in combination, a reciprocable bed, means to drive said bed in each direction, means to cause an appreciable rest after each movement of the bed, and means to start the bed from the position of rest to bring it gradually to desired uniform speed, to maintain said uniform speed, and gradually to bring it to a position of appreciable rest, a cylinder rotatable in one direction only, and means to drive said cylinder from said bed whereby the surface speed of the cylinder conforms in degree with that of the bed at all times during the described stroke of the bed.

15. A printing press comprising in combination, a reciprocable bed, an endless rack fast thereon, a cylinder having a gear, a driving shaft operatively connected to said cylinder gear, a driving gear fast on said driving shaft, a rotatory member loosely mounted on said shaft, a gear eccentrically mounted on said rotatory member and meshing with said driving gear and said endless rack, said parts being constructed, coöperating and operatively connected to drive the reciprocable member at a uniform speed during a part of its forward and backward strokes, and to cause it to remain appreciably at rest at the end of each of said strokes.

16. A printing press comprising in combination, a reciprocable bed, an endless rack fast thereon, a cylinder having a gear, a driving shaft operatively connected to said cylinder gear, a driving gear fast on said shaft, an intermittently rotatory member

concentric with said shaft, a gear eccentrically mounted on said rotatory member, and meshing with said driving gear and with said endless rack, said parts being constructed, coöperating and operatively connected to drive the reciprocable member at a uniform speed during a part of its forward and backward strokes, and to cause it to remain appreciably at rest at the end of each of said strokes.

17. A printing press comprising in combination, a reciprocable bed, an endless rack fast thereon, a cylinder having a gear, a driving shaft operatively connected to said cylinder gear, a driving gear fast on said shaft, a crank loose upon said shaft, a gear eccentrically mounted on said crank and meshing with said driving gear and with said endless rack, said parts being constructed, coöperating and operatively connected to drive the reciprocable member at a uniform speed during a part of its forward and backward strokes, and to cause it to remain appreciably at rest at the end of each of said strokes.

18. A printing press comprising in combination, a reciprocable bed, an endless rack fast thereon having reversely curved ends providing for appreciable period of rest, a cylinder having a gear, a driving shaft operatively connected to said cylinder gear, a driving gear fast on said shaft, a crank loose upon said shaft, a gear eccentrically mounted on said crank, and meshing with said driving gear and with said endless rack, and means for periodically locking said crank with respect to said driving shaft.

19. A printing press comprising in combination, a reciprocable bed, an endless rack fast thereon having reversely curved ends providing for appreciable period of rest, a cylinder having a gear, a driving shaft operatively connected to said cylinder gear, a driving gear fast on said shaft, a crank loose upon said shaft, a gear carried by said crank and meshing with said driving gear and with said endless rack, and means to lock said crank with respect to the driving shaft during the uniform speed portion of the strokes of said bed.

20. A printing press comprising in combination, a reciprocable bed, an endless rack fast thereto having reversely curved ends providing for appreciable period of rest, a driving shaft, a driving gear fast on said shaft, an intermittently rotatory member concentric with said shaft, a gear eccentrically mounted on said rotatory member and meshing with said driving gear and with said endless rack, means periodically to lock said rotatory member with respect to said driving shaft, said parts being constructed, coöperating and operatively connected to drive the reciprocable member at a uniform

speed during a part of its forward and backward strokes, and to cause it to remain appreciably at rest at the end of each of said strokes.

21. A printing press comprising in combination, a reciprocable bed, means to drive said bed in each direction, means to cause an appreciable rest after each movement of the bed, and means to start the bed from the position of rest to bring it gradually to desired uniform speed, to maintain said uniform speed and gradually to bring it to a position of appreciable rest, a cylinder driven in one direction only, and sheet delivery means driven from said bed.

22. A printing press comprising in combination, a reciprocable bed, means to drive said bed in each direction including means to start the bed from a position of appreciable rest to bring it gradually to the desired uniform speed, to maintain said uniform speed throughout the major portion of the movement of the bed in both directions of reciprocation, and gradually to bring it to a position of appreciable rest, a cylinder, means whereby the surface speed thereof conforms in degree to that of the bed, and sheet delivery means driven from said bed.

23. A printing press comprising in combination, a reciprocable bed, means to drive said bed in each direction, means to cause an appreciable rest after each movement of the bed, and means to start the bed from the position of rest to bring it gradually to desired uniform speed, to maintain said uniform speed and gradually to bring it to a position of appreciable rest, reciprocable sheet delivery means, a cylinder driven in one direction only, means whereby the surface speed thereof conforms to that of the bed, and means for driving said delivery means from said bed, and for bringing said delivery means gradually to a state of rest.

24. A printing press comprising in combination, a reciprocable bed, means to drive said bed in each direction, means to cause an appreciable rest after each movement of the bed, and means to start the bed from the position of rest to bring it gradually to desired uniform speed, to maintain said uniform speed and gradually to bring it to a position of appreciable rest, a cylinder rotatable in one direction only, means for causing the surface speed of the cylinder to conform in degree with that of the bed at all times during the described stroke of the bed, sheet delivery means, and operative connections between said sheet delivery means and said bed.

25. A printing press comprising in combination, a reciprocable bed, means to drive said bed in each direction including an endless rack upon said bed having reversed curved ends 44, 44, a driving shaft, a driving

gear fast thereon, a crank loose upon said shaft, a gear eccentrically carried by said crank and meshing with said rack and with its reversed curved ends and also meshing 5 with said driving gear and a longitudinally extending strip 15 coöperating with said crank to lock the same with respect to the driving shaft during the uniform speed travel of said rack in opposite directions, 10 but permitting the unlocking of the crank therefrom while the rack is being brought to positions of appreciable rest at said reversed curved ends 44, 44.

26. A printing press comprising in combination, a reciprocable bed, an endless rack carried thereby having reversed curved ends 44, and having reversed curved reversing shoes 9, 10, 12, 13, providing positions of appreciable rest, a driving shaft, a driving 20 gear fast on said shaft, a rotatory member concentric with but loose with respect to said shaft, a gear eccentrically mounted on said rotatory member and meshing with said driving gear and with said rack, and a longitudinally extending strip 15 with which said rotatory member is operatively engaged during travel of said reciprocable member in each of two opposite directions but permitting disengagement therefrom while said 30 gear eccentrically mounted upon the rotatory member is engaged with the reversed curved end portions of said rack.

27. A printing press comprising in combination, a reciprocable bed, a cylinder rotatable in one direction only and means for causing the surface speed of the cylinder to conform in degree with that of the bed throughout the entire stroke of the bed, and including means whereby the bed is driven 35 at a uniform speed throughout a portion of its movements in both directions of reciprocation.

28. A printing press comprising in combination, a reciprocable bed, means to drive said bed in each direction, means to cause an appreciable rest after each movement of the bed, and means to start the bed from the 45 position of rest, to bring it gradually to desired uniform speed, to maintain said uniform speed through a portion of the movement of the bed in both directions of reciprocation, and gradually to bring it to a position of rest, a cylinder, and means for causing the surface speed of the cylinder to conform in degree with that of the bed at all 50 times during the described stroke of the bed.

29. A printing press comprising in combination, a reciprocable bed, means to drive said bed in each direction, means to cause an 60 appreciable rest after each movement of the bed, and means to start the bed from the position of rest, to bring it gradually to desired uniform speed, to maintain said uniform speed throughout a portion of the 65 movement of the bed in both directions of

reciprocation, and gradually to bring it to a position of rest, a cylinder rotatable in one direction only, and means for causing the surface speed of the cylinder to conform in degree with that of the bed at all times during the described stroke of the bed. 70

30. A printing press comprising in combination, a reciprocable bed, means to drive said bed in each direction, means to cause an appreciable rest after each movement of the 75 bed, and means to start the bed from the position of rest, to bring it gradually to desired uniform speed, to maintain said uniform speed throughout a portion of the movement of the bed in both directions of 80 reciprocation, and gradually to bring it to a position of appreciable rest, a cylinder rotatable in one direction only, and separable from the bed during the non-active stroke of the bed, and means to drive said cylinder 85 from said bed whereby the surface speed of the cylinder conforms in degree with that of the bed at all times during the described stroke of the bed.

31. A printing press comprising in combination, a reciprocable bed, means to drive said bed in each direction, means to cause an appreciable rest after each movement of the bed, and means to start the bed from the 90 position of rest, to bring it gradually to desired uniform speed, to maintain said uniform speed throughout a portion of the movement of the bed in both directions of reciprocation, and gradually to bring it to a position of appreciable rest, a cylinder rotatable in one direction only, and means for causing the surface speed of the cylinder to conform in degree with that of the bed at 95 all times during the described stroke of the bed, and including means to bring said cylinder to a position of rest at each end of the 100 stroke of the bed.

32. A printing press comprising in combination, a reciprocable bed, means to drive said bed in each direction, means to cause an 110 appreciable rest after each movement of the bed, and means to start the bed from the position of rest, to bring it gradually to desired uniform speed, to maintain said uniform speed throughout a portion of the movement of the bed in both directions of reciprocation and gradually to bring it to a 115 position of appreciable rest, reciprocable sheet delivery means, and operative connections between said means and said bed to drive said means at the same rate of speed as said bed and gradually to bring said delivery means to a state of rest at the end of the outward stroke of said delivery means.

33. A printing press comprising in combination, a reciprocable bed, means to drive said bed in each direction, means to cause an appreciable rest after each movement of the bed, and means to start the bed from the 125 position of rest, to bring it gradually to de- 130

- sired uniform speed, to maintain said uniform speed throughout a portion of the movement of the bed in both directions of reciprocation and gradually to bring it to speed during a part of its forward and backward strokes and to cause it to remain appreciably at rest at the end of each of said strokes.
35. A printing press comprising in combination, a driving shaft having a driving member, a reciprocable bed, and means associated with and operatively connecting said driving member and said reciprocable bed and including a member concentric with said driving shaft and having a part eccentric with respect to the driving shaft, to effect driving of said bed at a uniform speed during a part of its forward and backward strokes and to cause it to remain appreciably at rest at the end of each of said strokes. 25 30 35
- 5 a position of appreciable rest, a cylinder, means for causing the surface speed of the cylinder to conform in degree with that of the bed at all times during the described stroke of the bed, sheet delivery means and 10 means to drive said delivery means from said bed.
34. A mechanical movement comprising a driving shaft having a driving member, a reciprocable member, and means associated 15 with and operatively connecting said driving member and said reciprocable member and including a member concentric with said driving shaft and having a part eccentric with respect to the driving shaft, to effect the driving of the latter at a uniform

In testimony whereof, I have signed my name to this specification.

WILLIS K. HODGMAN, JR.
